UNITED STATES PATENT OFFICE.

OWEN DONNELLY AND COTTER T. BRIDE, OF WASHINGTON, DISTRICT OF COLUMBIA.

METHOD OF CLEANING PIPE SEWERS.

SPECIFICATION forming part of Letters Patent No. 402,662, dated May 7, 1889.

Application filed January 22, 1889. Serial No. 297,135. (No model.)

To all whom it may concern:

Be it known that we, OWEN DONNELLY and COTTER T. BRIDE, citizens of the United States, residing at Washington, in the District of Columbia, have invented certain new and useful Improvements in Method of Cleaning Pipe Sewers; and we do hereby declare the following to be a full, clear, and exact description of the invention, such as will enable others skilled in the art to which it appertains to make and use the same.

This invention relates to certain new and useful improvements in method of cleaning sewers and conduits, substantially as will hereinafter be more particularly described or pointed out.

In many instances heretofore, when it has been desirable to clean or clear the passages of pipe sewers by the use of any of the various apparatus in use for the purpose, it has frequently been found difficult and in many instances practically impossible to obtain a passage-way for the draw cable or rod, and in such instances where the same has been accomplished or effected it has only been after the expenditure of considerable manual labor coupled with great expense and considerable loss of time.

The object of our invention is to supply a simple method of cleaning pipe sewers or conduits in a very quick and effective manner, as will be hereinafter more fully understood when taken in connection with the accompanying drawings, which illustrate suitable mechanism for carrying the same into effect, and wherein—

Figure 1 represents a sectional view of a part of a pipe-sewer system and indicating the practice of one step of our improved method, and Fig. 2 is a similar view representing the manner in which the second step of our improved method is practiced. Fig. 3 is a view in perspective of the form of cleaning device preferably employed by us, and Fig. 4 is also a perspective view of another device preferably employed.

In the practice of our invention we start or begin at any man-hole of the sewer system, and take what we term or style a "starting" implement or tool for creating an opening

through the clogged interior of the section started with, and trailing along with it a rope, chain, or cable. This starter is forced or propelled forward by power apparatus located above or at the top of the man-hole until it 55 has been projected in a distance about equal to its own length. After this another length or piece is attached or screwed to the outer end of the first length or piece, and the same operation of forcing or projecting them into 60 the sewer is repeated. Additional lengths are added one after the other, and the forcing or propelling of them along, into, and through the accumulations of the sewer continued until the innermost section has reached 65 the next adjacent man-hole, whereupon the sections are pulled through length for length and separated or disconnected from each other.

During the progress of the above-described step of the operation it will be understood 70 that a rope or cable is trailed through the sewer as the starter is projected along, and when the man-hole adjacent to the one started from is reached the end of such rope or cable is attached to the propelling apparatus located above, (which apparatus, it will be understood, has been moved to this second man-hole,) and by operating the same it is made to draw or pull through the sewer a suitable cleaning apparatus attached to the opposite 80 end of said rope or cable, and thus will the cleaner be drawn through from the first man-hole to the second. The same operation is repeated with the several sewer-sections until the entire system has been worked or cleaned. 85

As further explanatory of our improved method and the manner herein described of practicing the same, we would say that we use the same apparatus for drawing the cleaning device through that we employ for propelling 90 or projecting the starter through, the said apparatus in the one instance being a draft-power and in the other a propelling-power, the difference in its action being due to the change made in its location from the man-hole at 95 which the starter is introduced to the one from which it is taken for the purpose of drawing the cleaning device through.

As one means of practicing our improved method, we resort preferably to the use of such 100

form of starter and cleaning device as is shown in our application filed December 21, 1888, and bearing Serial No. 294,302, the accompanying drawings also representing the same.

5 In the drawings, *a* indicates the first section of starter, the same having attached thereto an end of the cord *b* that is trailed through the sewer, and to the other end of which the cleaning device *A* is afterward attached for 10 the purpose of being drawn through the sewer to cut up the accumulations thereof and drag the same along, so as to be readily removed or taken out at the several man-holes.

15 *c* represents the remaining sections of said starter.

The cleaning device *A* is constructed substantially as herein shown and as described in our other application referred to.

20 In the practice of this our present invention we also make use of the platform *E* at the bottom of the man-holes, and which is shown in Fig. 4. This platform also is constructed as herein shown, and more particularly described in our other application, and 25 need not herein be more particularly described or referred to, except by saying that its pulley serves to guide the cable *n*, employed to propel or project the starter, as well also as

the rope or cable *b*, for drawing the cleaning apparatus through, the one being drawn out 30 for the accommodation of the other, and vice versa.

Having thus described our invention, what we claim as new, and desire to secure by Letters Patent, is—

35 The method herein described of cleaning pipe sewers, which consists, first, in mechanically projecting a starting implement into the sewer by means of power apparatus located above, and simultaneously trailing along with 40 said starter a draft cable or rope, then successively attaching additional lengths to the starter and repeating the forcing of them into the sewer mechanically, as before, and finally attaching to the rear end of said draft cable 45 or rope a suitable cleaning device and drawing the same through the sewer, substantially in the manner and for the purpose set forth.

In testimony whereof we affix our signatures in presence of two witnesses.

OWEN DONNELLY.
COTTER T. BRIDE.
